UNITED STATES PATENT OFFICE.

WILLIAM C. HIERING, OF NEWARK, NEW JERSEY, ASSIGNOR TO J. E. MERGOTT CO., OF NEWARK, NEW JERSEY, A CORPORATION OF DELAWARE.

COMBINED CLASP, CATCH, AND LOCK FOR BAGS.

Application filed January 22, 1926. Serial No. 82,942.

This invention relates to bag fastening devices, with special reference to bags having a pair of hinged, channel frames and has as one of its objects to provide a neat and efficient fastener, unique in that it fulfills the functions of a clasp, a positive lock and a catch operable irrespective of the lock.

It is a further feature to produce a fastener in which substantially all parts are composed of sheet metal by ordinary stamping processes, insuring uniformity and economy in manufacture.

Another aim is in the provision of a key actuated lock by which security is attained when desired and which is independent relatively of the clasp and catch functions.

These characteristic features are achieved in the present embodiment by the original design, combination and relation of parts as hereafter described in detail and delineated in the associated drawing, the same being a constituent part hereof, and in which:

Figure 1 is a perspective view of an embodiment of the invention illustrating its application to a conventional type of bag frame.

Figure 2 is a longitudinal central sectional view thereof.

Figure 3 is a bottom plan view of the fastener showing the parts therein.

Figure 4 is a bottom plan view of the mechanism taken on a plane indicated by the line 4—4 of Fig. 2.

Referring now more in detail to the drawing, the numerals 10 and 10' designate the two channel shaped members of the bag frame, which are hingedly connected at their ends in the usual manner.

An anchor plate 11 is rigidly secured to one of the pair of frame members, as 10', its outer end being coiled to present a hinge eye 12, through which a hinge pin 13 extends.

Curled to encircle the ends of the pin 13 are corresponding eyes 14 formed on the end of a plate 15, slightly wider than the combined width of the frame elements 10, 10', over which the plate extends at a spaced distance thereabove.

Fixed rigidly on the lower side of the plate 15 are a pair of clasp plates 16, arranged in spaced parallel relation and adapted to embrace between them the frame elements 10, 10', these plates being connected

at the front by a narrow strip 17 attached 55 to the hinged plate 15.

Rigidly mounted on the upper side of the plate 15 is a low rectangular casing 18 in which the catch and lock mechanism is carried.

The catch mechanism is composed of a flat slide 19 having a raised transverse flange 20 at its rear edge, the same extending to the inner side of the top plate of the casing 18.

Fixed in the bottom of the slide 19 is a 65 hook catch 21, the same passing through an opening 22 in the plate 15 and having a bevelled lower edge 23 adapted to engage the loop of a keeper 24 fixed on the frame member 10, the shape of the catch being such as 70 to snap past the upper part of the keeper and engage therein when the plate and casing are turned down on the axis of the hinge pin 13.

An arcuately bent flat spring 25, in the 75 casing 18 abuts the flange 20 of the catch carrying slide 19, normally urging the same forward to cause engagement of the catch and keeper, the spring being held in fixed relation to the slide, due to being rigidly set 80 in a slot in its edge.

Movable closely against the under side of the casing top is a push plate 26, the central portion of its rear end being in contact with the flange 20 and its upwardly curved, narrowed forward end 27 extending through the front wall of the casing 18 to be manually operated in compressing the spring 25 and releasing the catch from its keeper.

Movable transversely in the rear of the 90 casing is a cross slide 28 having forwardly extending spaced arms 29, 29' movable on the plate 15 and actuated by the ward 30 of a key 31 enterable through an opening 32 in the top plate of the casing 18.

Another arm 33, extends from the upper portion of the cross slide 28, the arm being movable by actuation of the key 31 into and out of the path of finger 34, extending rearwardly from the inner end of the push plate 26, to intercept its movement when in one position and permit it to be moved by the fingers of an operator when in another position.

It will be noted that the free end of the 105 spring 25 acts as a frictional brake for the cross slide 28, retaining it in either of its adjusted positions, in addition to pressing the

catch carrying slide 19 in a forward position, and, through the flange 20, urging the push plate 26 forward.

As has been stated, when the cross slide 28, which may be considered as a detent or controller, is moved to one side of the casing the push plate may be pressed inwardly, causing the catch carrying slide to retract and free the keeper 24, thus permitting the bag to be opened upon swinging the clasp and associated parts upwardly on the hinge axis 13.

When the controller slide 28 is at the other side of the casing the push plate 26 cannot be moved back and therefore the detent hook 21 will be retained in the keeper, this being the locked position of parts.

However the slide 19 and detent hook 21 are at all times movable rearwardly, permitting the hook to engage the keeper 24 upon closing the clasp on its hinge, irrespective of the position of the controller slide, thus engaging the catch, without respect to the position of the key actuated parts.

Although I have described my improvements with considerable detail and with respect to certain particular forms of my invention, I do not desire to be limited to such details since many changes and modifications may well be made without departing from the spirit and scope of my invention in its broadest aspect.

Having thus described my invention, what I claim is new and desire to secure by Letters Patent, is:—

1. A combined clasp, catch and lock for bags comprising a channel shaped clasp hingedly engaged with one of a pair of bag frame members and adapted to straddle both members, a keeper fixed in said frame member, a casing carried by said clasp, a slide in said casing, a catch carried by said slide to engage said keeper, a push plate to retract said slide, a detent movable transversely in said casing into and out of the path of said push plate, key operated means for moving said detent, and a single curved flat spring to normally expel said slide, said spring frictionally engaging said detent to retain it in adjustment.

2. A combined clasp and catch for bags comprising a plate hinged to one of a pair of bag frame members, a keeper fixed on said member, a pair of frame embracing members extending rigidly from said plate, a slide carrying a catch hook passing through said plate to engage said keeper, a spring urging said slide into position to cause engagement of said catch hook and keeper, and a push plate associated with said slide by which the catch hook may be withdrawn from said keeper, said slide being operative independent of said push plate.

3. A bag lock comprising a plate hinged to one of a pair of bag frame members, means on said plate to embrace the pair of frame members, a keeper on one of said members, a catch slidably connected with said plate, a spring fixed at one end in said catch to press it into engagement with the keeper, a push plate to retract said catch, a control slide movable transversely on said plate, said slide having a slot in its rear edge in which one end of said spring is fixed, said slide preventing movement of the push plate when in one position, and key actuated means for operating said control slide.

4. A bag lock comprising a plate hinged to one of a pair of bag frame members, means on said plate to embrace the pair of frame members, a keeper on one of said members, a casing on said plate, a catch having a part slidable in said casing, a push plate extending through the front of said casing, said push plate being in operative contact with said catch to retract the same, a control slide mounted transversely in said casing, means on said slide to intercept movement of said push plate when in one position and permit movement thereof when in another position, said slide having a slot in its rear edge, a curved flat spring fixed at one end in the slot to retain the slide in an adjusted position, the other end of said spring abutting said catch to normally project it outward, and key operated means to shift said control slide.

This specification signed this 19th day of January, 1926.

WILLIAM C. HIERING.
